UNITED STATES PATENT OFFICE.

CHARLES F. SMITH, OF NEW BRITAIN, CONNECTICUT.

TABLEWARE.

1,080,661.

Specification of Letters Patent.

Patented Dec. 9, 1913.

Application filed March 17, 1911. Serial No. 615,022.

To all whom it may concern:

Be it known that I, CHARLES F. SMITH, a citizen of the United States, and a resident of New Britain, in the county of Hartford, State of Connecticut, have invented certain new and useful Improvements in Tableware, of which the following is a specification.

The invention relates to certain improvements in table ware, such as knives, forks, etc., and particularly to the construction of the handle, and its attachment to the blade, the object being to reduce the cost of manufacture and at the same time produce an article entirely satisfactory as to strength and general appearance.

In the drawings Figure 1 is a view of the handle blank. Fig. 2 is the same after the first operation. Fig. 3 is the same after the second operation. Fig. 4 is a view of the blade. Fig. 5 is a view of the completed article. Fig. 6 is a partial sectional view on line 6, 6 of Fig. 5. Fig. 7 is a partial sectional view taken at right angles to that of Fig. 6.

In carrying out my invention, the handle blank A is first cut out of sheet metal to the form shown in Fig. 1. It is next shaped by proper dies to the form shown in Fig. 2. It is next bent up into approximately finished shape as shown in Fig. 3, the abutting edges of the handle being separated sufficiently to permit of the insertion of the tang of the blade. There is thus produced a handle having formed integrally with it a bolster B connected by the reduced neck C. The handle as thus far completed is now thoroughly tinned inside and out. The blade D has a tang E with notches F F in its edges, the tang end of the blade being tinned to about the point indicated by the dotted lines X X. The tang of the blade is now inserted in the handle with its notches registering with the reduced neck C. The handle is next closed down onto the tang and its abutting edges set firmly together by a swaging operation causing the sides of

the reduced neck to bear upon the sides of the tang and the edges interlock with the notches in the edges of the tang, to securely position the blade. The handle is again immersed in a tinning bath which securely solders the abutting edges of the handle together and the bolster to the blade. The small aperture A' which is necessary in order to give the proper form to the reduced neck portion is closed up in the setting and tinning operations.

The handle and the tang end of the blades having been thoroughly tinned before assembling, the final tinning operation after the parts are assembled effects a thorough and complete soldering of the contacting edges of the handle and the contacting surfaces of the handle and the blade, strengthening the completed article and effectually closing all openings in the handle preventing the entrance of water or the accumulation of foreign substances.

I claim as my invention:

An article of table ware comprising a handle formed from a sheet metal blank, with two similarly shaped and oppositely arranged hollow side members, a blade provided with a short flat tang fitting within one end of said handle, oppositely extending projections from the sides of the handle near one end thereof adapted to engage the sides of said shank at spaced points to clamp it in position, projections from the edges of the handle, adjacent to the first mentioned projections and adapted to engage and interlock with notches in the edges of the shank, and a coating of fusible material covering the surfaces of the handle and the shank of the blade and adapted to unite the contacting surfaces both of the handle and of the shank and handle.

CHARLES F. SMITH.
